(57) **CLAIM**

I claim the ornamental design for a T-angle drill, as shown and described.

DESCRIPTION

FIG. 1 is a front perspective view of a first embodiment of a T-angle drill of the present invention;

FIG. 2 is a first side view thereof;

FIG. 3 is a second side view thereof;

FIG. 4 is a front view thereof;

FIG. 5 is a rear view thereof;

FIG. 6 is a top view thereof;

FIG. 7 is a bottom view thereof;

FIG. 8 is a front perspective view of a second embodiment of a T-angle drill of the present invention;

FIG. 9 is a first side view thereof;

FIG. 10 is a second side view thereof;

FIG. 11 is a front view thereof;

FIG. 12 is a rear view thereof;

FIG. 13 is a top view thereof; and,

FIG. 14 is a bottom view thereof.

Any broken lines in the drawings are for illustrative purposes only and form no part of the claimed design.
